CLAIM

The ornamental design for a night light, as shown and described.

DESCRIPTION

FIG. 1 is a front, left perspective view of a night light, showing my new design;

FIG. 2 is a rear perspective view thereof;

FIG. 3 is a front, right perspective view thereof;

FIG. 4 is a rear, bottom perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

The even dashed broken line shown in the drawings are included for the purpose of illustrating portions of the night light that form no part of the claimed design.

1 Claim, 10 Drawing Sheets
